CLIP RACK FOR SUSPENDING COLLAPSIBLE TUBES FROM A CABINET SHELF

Victor J. Bardon, 9438 Oakmore Road,
Los Angeles 35, Calif.

Filed May 17, 1963, Ser. No. 74,926

Term of patent 14 years

(Cl. D4—3)

FIG. 1 is an isometric view of a clip rack for suspending collapsible tubes from a cabinet shelf showing my new design;

FIG. 2 is a side elevational view;

FIG. 3 is a plan view;

FIG. 4 is an inverted plan view;

FIG. 5 is an elevational view of the left end thereof as seen in FIG. 2; and

FIG. 6 is an end elevational view of the right end thereof as seen in FIG. 2.

I claim:

The ornamental design for a clip rack for suspending collapsible tubes from a cabinet shelf, substantially as shown.
